PORTABLE HAMMER

Ragnar E. Skoglund, Chicago, Ill.

Application June 7, 1940, Serial No. 339,351

15 Claims. (Cl. 153—48)

This invention relates to hammers and more particularly to portable mechanical hammers having a reciprocable hammer element and adapted to be operated from an electrical motor or other suitable power source by means of a flexible shaft. The invention is particularly adapted for straightening sheet metal, such as automobile bodies and fenders, or for riveting, calking, chiseling, and the like. It may be successfully used as a stone cutting tool or for any other purpose where a high speed short stroke hammer is required.

It is an object of the invention to provide a power-operated hammer of the character described which may be hand-controlled and provided with a suitable anvil and support therefor, and in which the anvil support is adjustable and removable from the hammer unit so that the device may be usable for operation on work which would otherwise be inaccessible. For instance, the device including the hammer unit and removable anvil support are so constructed that the hammer and anvil may be positioned for operation on irregularly shaped sheet metal such as automobile fenders and the like, and the anvil may be adjusted relative to the hammer so that the elements properly may co-operate to straighten the material by removing otherwise inaccessible dents or doing any other work for which the device is adapted.

Another object is to provide a hand-controlled portable hammer and anvil and support therefor in which the anvil and its support may readily be separated from the hammer unit, so that the hammer may be used for various types of work in which an anvil may not be required, and in which the separation may be accomplished merely by an angular movement of the hammer handle.

Another object is the provision of a portable power operated hammer which may be operated at high speed and the operation of which may at all times be under the control of the operator. In fact, in the embodiment illustrated, the power is continuously supplied to the hammer from any suitable power source through a flexible shaft, and the operation of the hammer element per se may be controlled by the same hand of the operator which is holding the hammer in position for work.

Another object is the provision of a hammer operated by means of a continuously rotating shaft in which the energy for operating each working stroke of the hammer element is stored while the hammer element is stationary at the

work end of its stroke and the element is then raised and the stored energy released to perform a working stroke of the hammer element. In other words, the energy is stored with the hammer element at the bottom of its stroke and is released with the hammer element at the top of its stroke.

Another object is the provision of a new and novel energy storing and hammer tripping transmission between the flexible shaft and the hammer element which will alternately store energy and raise and trip the hammer element to release the stored energy and in which the storing and tripping mechanism is normally ineffective and may be made effective by an easily controlled trigger arrangement under the control of the operator.

A further object is the provision of a hammer of the character described which will be of comparatively small size, of few parts, easy to assemble and disassemble, and which will not easily get out of order in use.

Further objects will be apparent from the specification and the appended claims.

In the drawings:

Fig. 1 is a side elevation of one embodiment of the invention adapted for connection to a suitable power source, not shown, by means of a flexible shaft drive.

Fig. 2 is a sectional elevation of the adjustable connection between the upper and lower arms of the anvil supporting frame or yoke shown in Fig. 1.

Fig. 3 is a top view of the embodiment illustrated in Fig. 1 and illustrates the required movement of the hammer unit in order to separate this portion from the anvil supporting frame.

Fig. 4 is a vertical sectional view through the hammer head and anvil support illustrated in Fig. 1 and is taken on a line substantially corresponding to line 4—4 of Fig. 3.

Fig. 5 is a fragmentary sectional view taken on a line substantially corresponding to line 5—5 of Fig. 4.

Fig. 6 is a perspective view of the spring loading yoke which is slidably supported in the hammer element.

Fig. 7 is a perspective view of the hammer trip control block which is supported on the yoke illustrated in Fig. 6 and which is adapted to be moved by the trigger to control the operation of the hammer.

Fig. 8 is a vertical sectional view of the assembled floating pivot elements shown in Figs. 6 and 7 and is taken on line 8—8 of Fig. 6.

Fig. 9 is a vertical sectional view taken on a line substantially corresponding to line 9—9 of Fig. 4 with the hammer operating mechanism shown in full lines.

Fig. 9A is a somewhat diagrammatic perspective view of the hammer and operating mechanism, a portion of the casing and other elements being shown in section.

Fig. 10 is a diagrammatic view illustrating the movement of the spring loading and hammer operating trip when it is retained in hammer operating position by means of the manually controlled trigger.

Fig. 11 is a diagrammatic view similar to Fig. 10, but illustrates the normal position and operation of the loading and trip member when the controlling trigger is not depressed and the hammer is not in operation.

Fig. 12 is a top view of the hammer element and upper bearing assembly.

Fig. 13 is a detail sectional view taken on line 13—13 of Fig. 12.

Referring to the drawings in detail, the embodiment illustrated comprises an elongated vertical hammer housing or casing 1, which includes, preferably integrally therewith, a laterally extending handle 2 by which the entire device may be supported and positioned by one hand of the operator and controlled for operation in a manner which will later be described. A flexible shaft casing 3 is connected to the handle 2 and a flexible shaft 4 of any suitable type is supported within the casing in the usual manner, and this flexible shaft is adapted to be connected to any suitable power source such as an electric motor, not shown.

An anvil supporting yoke is removably connected to the casing 1 and comprises an upper yoke arm 5 and an anvil supporting arm 6 adjustably connected thereto in the manner illustrated in Fig. 2. The arm 6 is preferably shaped somewhat as shown in order that the yoke may accommodate therein various sheet metal shapes to which the hammer may be applied, and this arm 6 is provided at its outer end with a cup-shaped portion 7 having an anvil 8 supported therein by means of a compression spring 9 (Fig. 4). This provides a somewhat resilient anvil which is in axial alignment with the casing 1 and the hammer element supported therein. The anvil 8 is provided with retaining pins 8a whereby the anvil may be inserted in the cup by means of clearance slots 8b and then turned 90 degrees as shown.

As shown in Fig. 2, the anvil may be adjusted relative to the hammer by raising or lowering the arm 6 by means of an ornamental knurled hand wheel 10 having a hollow stem 11 mounted in the upper arm 5 and rotatably secured therein by means of a lock screw 12 extending into an annular groove 13 in the hollow stem. A post 14 is secured in the lower arm 6 by means of a pin 15 or other means, and extends upwardly into the hollow stem 11. The stem 11 is provided with a cam slot 16 into which a pin 17 secured in the post 14 extends. The cam slot may be of any suitable shape so that, by rotation of the hand wheel 10, the lower arm 6 may be raised or lowered to position the anvil as desired relative to the hammer.

An arm aligning post 18 is rigidly secured in the lower arm 6 in any suitable manner and extends into a suitable bore in the upper arm 5 as shown. The post 18 is provided with an annular flange 18a, and a spring 19 tends to urge the

arms 5 and 6 apart and to retain them in fixed adjusted relation. The parts are all retained in assembled relation by means of a threaded bushing 20.

As previously stated, the anvil supporting yoke is arranged to enable positioning of the device with respect to irregular sheet metal surfaces such as automobile fenders, so that the hammer and anvil may properly be located with respect thereto to accomplish the work desired. In some instances, the material is of such shape that it is difficult to insert the material between the anvil and hammer and in position between the arms of the anvil supporting yoke. The anvil supporting yoke and the hammer unit are, therefore, adapted to easily be separated by means of the releasable connecting elements illustrated in Figs. 1, 4, and 5. These elements comprise an upwardly extending pivot pin 21 which is rigidly secured in the arm 5 preferably by means of a pin 22. The housing 1 is pivotally mounted on the pivot pin 21, as shown in Fig. 4, and is normally retained thereon by means of a taper pin 23 in the housing and extending into a groove 24 in the pivot pin. The slot 24 is limited in extent as shown in Fig. 5 and terminates in a cut-away flat side 25 of the pivot 21, so that, when the casing is turned 90 degrees, as illustrated by dotted lines in Fig. 3, the elements may easily be separated.

The yoke arm 5 is provided with an upwardly extending horizontally arcuate dovetail portion 27 which is adapted to engage in a complementary dovetail slot 28 in the underside of the handle 2, whereby, when the parts are assembled and the hammer unit moved to the full line position shown in Figs. 1 and 3, the housing and yoke are locked together by means of the pivot pin and the dovetail arrangement.

A reciprocable hammer element 29 is mounted in the casing 1 and provided with a hammer head 29a in a suitable bearing in the lower end of the casing. The hammer stroke is comparatively short, preferably only about one-eighth of an inch, and the hammer head 29a projects below the lower edge of the housing 1 approximately one-half of the length of the stroke, that is, about one-sixteenth of an inch. It has been found that this provides the best operating relationship of the hammer for the reason that, when this relationship is maintained, the casing performs a function somewhat similar to that of a stripper when the hammer is in operation on sheet metal inserted between the anvil and the hammer. That is, the metal tends to follow the hammer upwardly, and, if the hammer extends materially below the casing, extreme vibration of the material worked on tends to reduce the efficiency of the hammer in so far as accurate straightening of the material is concerned. It is, therefore, an important feature of the present invention to provide a relationship wherein the hammer, particularly when used for sheet metal work, never extends below the bottom of the casing more than a comparatively small portion of the stroke.

The hammer head 29a may be secured to the body of the hammer element by means of a taper pin 30 and the hammer head may be removed and replaced by a similar head or a head of any desired type by removing the screws 31 (Fig. 9) and then removing the taper pin 30 through one of the openings provided by removal of the screws.

The hammer element 29 is in the form of a yoke, as shown in Figs. 9 and 9A, and provided with an opening 32 therethrough to receive the

drive shaft and operating mechanism. The hammer element is also provided on each side with a vertical slot 33 for guiding a loading yoke 34 which is slidably mounted therein and which will be described later.

The upper end of the hammer element 29 is provided with a reduced portion 35 which is slidably mounted in a suitable bearing 36 which latter may be secured in the casing by means of a press fit or otherwise, as desired, and may be secured against rotation by a setscrew 36a (Fig. 13). A feather key 37 is mounted in the shaft and engages in the bearing 36 to prevent rotation of the hammer and maintain it in proper alignment with the other operating elements. An adjustable plate 38 is slidably mounted on adjustable studs 39 threaded into the bearing 36, and springs 40 are positioned on the studs and between the plate 38 and the bearing 36 so that the plate 38 may be adjusted by means of the studs 39 to provide any desired compression of the springs 40. A cap nut 41 is threaded on the upper end of the hammer element, as shown, and normally rests on the spring-supported plate 38 when the hammer is in its normal lowered position. The screws 39 are locked against rotation by means of an octagonal washer 39a (Fig. 12) which engages the flat side of each screw head. Pins 38a may be provided in the plate 38 and serve as stops to limit the downward movement of the hammer element if the springs 40 become weakened.

A transverse shaft 42 extends through the opening 32 in the hammer element and is supported in suitable bearing bushings 43 and 44, as shown in Fig. 4, and the terminal of the flexible shaft 4 may be connected thereto by any suitable means, for instance, such as the threaded coupling 45. The shaft 42 will, therefore, be continuously driven and is provided with an eccentric 46, preferably integral therewith. This eccentric is in alignment with the hammer element, as illustrated, and an eccentric strap forming a trip member 47 is mounted on the eccentric and provided with an upwardly extending trip lug or pawl 48. The pawl portion 48 is adapted, during operation of the eccentric, to co-operate with a downwardly extending lug 49 which is preferably a hardened steel insert in the hammer element 29.

The lower side of the eccentric strap 47 is provided with a spiral or angular gear tooth slot 50 which is in mesh with an upwardly extending complementary tooth 51 such as an involute or epicycloid gear tooth on a trip control block 52. This tooth 51 provides a pivot on which the strap 47 oscillates during rotation of the eccentric. The upwardly extending tooth 51 is an integral portion of a laterally movable trip control block 52 (Fig. 7), which latter is provided with transverse holes 53, whereby the block may be slidably mounted in the opening 34a of the previously mentioned loading yoke 34, as shown in Figs. 6 and 7, the pins being riveted over at their ends after assembly to limit the sliding movement of pivot block 52 as shown in Fig. 8. Coil springs 55 are mounted on the pins 54 between the trip control block 52 and the loading yoke 34 to normally hold these blocks separated so that the angular pivot tooth 51 is normally in the position shown in Fig. 11, whereby the hammer element is inoperative during rotation of the eccentric as the pawl 48 will not engage the hammer lug 49. The block 52 is provided with a bearing portion 56 (Fig. 7) which extends in-

to and is slidably supported in a beveled opening 57 in the loading yoke.

The loading yoke 34 is provided with downwardly extending legs 58 which are slidably mounted in the slots 33 in the hammer element, as shown in Fig. 9A. The lower ends of these legs 58 are secured to a ring 59 by means of pins or screws 59a, as shown in Fig. 4. The ring 59 is slidably mounted on the hammer element 29 and a comparatively heavy compression spring 60 is mounted between the ring and the hammer head 29a, whereby the loading yoke 34 and the laterally movable pivot tooth 51 slidably mounted thereon are normally urged upwardly against the eccentric ring to retain the teeth in mesh, as shown. Therefore, with each rotation of the eccentric, the teeth will be retained in mesh to oscillate the eccentric pawl, and the block 52, loading yoke 34, and ring 59 will be moved downwardly to compress the spring 60.

As previously stated, the trip control block is normally held by means of the springs 55 in its outward position shown in Figs. 4 and 8, and in this position, due to the angular relationship of the tooth slot 50 and pivot tooth 51, the eccentric strap and lug 48 thereon will operate in the position shown in Fig. 11 relative to the lug 49 on the hammer element. With the tooth 51 in this position, the point or tripping edge 61 of the tripping lug 48 will, with each revolution of the eccentric, travel in the substantially elliptical path shown by the dotted line 62 and in the direction of the arrowheads and will, therefore, not engage the hammer lug 49, and the hammer will not be operated although the eccentric is continuously rotated.

In order to provide a manual control to push the trip control block 52 inwardly so that the angular pivot tooth 51 will position the eccentric strap as shown in Figs. 9A and 10 to thereby operate the hammer element, a sliding pin or rod 63 (Figs. 4 and 9A) is slidably mounted in a bushing 64 in the casing 1 and with its forward end resting against the trip control block 52. A trigger 65 is pivoted at 66 and provided with a hardened steel portion 67 bearing against the opposite end of the sliding pin 63. This trigger 65 is normally urged downwardly to the position shown in Fig. 4 by means of a spring 68. The curved forward end of the yoke arm 5 is releasably connected to the hammer unit and forms a trigger guard to prevent accidental operation of the trigger 65 as shown in Figs. 1 and 4.

As previously stated, with the parts in the position illustrated in Figs. 4 and 11, the eccentric may be continuously rotated without operating the hammer element. When it is desired to operate the hammer element, the trigger 65 is pressed upwardly by the hand of the operator and the sliding pin 63 will force the trip control block and the angular pivot tooth thereon inwardly so that the eccentric strap and trip pawl 48 thereon are positioned as shown diagrammatically in Fig. 10. This rotary positioning of the cam strap is due to the angular or spiral relationship of the gear teeth, whereby lateral movement of the teeth will rotarially position the eccentric strap. In this position shown in Figs. 9 and 10, the edge or point 61 of the tripping pawl will move in the substantially elliptical path 69 in the direction of the arrowheads, and, therefore, with each revolution of the eccentric, the pawl 48 will engage un-

der the hammer lug 49 and raise the hammer and then release it for a working stroke.

A cap 70 is threaded on the top of the casing 1, as shown in Fig. 4, and forms a part thereof. The cap may easily be removed to provide access to the adjustable screws 39 and to enable convenient assembly of the mechanism. The casing 1 is intended to be filled with lubricant and is properly sealed by means of a packing ring 71 around the hammer head and suitable gaskets are used wherever needed. A steel bushing 72 is threaded into the handle 2 and the flexible shaft casing is secured therein by a coupling 73. The bushing 72 retains bearing bushings in assembled relation at all times.

A desirable feature of the present invention is the fact that the hammer element 29 is not at any time raised against the compression of a spring. Instead, energy for operating the hammer element is stored in the spring 60 only when the hammer element is stationary at the bottom limit of its working stroke. During the loading movement of the eccentric and associated parts, the bearing pressure is only on the upper side of the shaft 42. After the spring is loaded, the pawl lug 48 passes under the hammer lug 49 and raises the spring loaded hammer. Therefore, during the upward movement of the eccentric, the load on the bearings is substantially equalized. In other words, the hammer element is raised without any spring pressure applied to the shaft or bearings.

An important feature of the invention is the method of assembly. The hammer element and loading elements provide a sub-assembly which is first inserted in the casing and properly supported therein by means of the springs 40 and associated elements, including the nut 41. The shaft 42 and assembled bushings are then inserted through the handle 2 and locked in place by means of the steel bushing 72. There is no lateral pressure on the shaft 42 and associated driven elements. The hammer may be directly connected to a motor if desired. A satisfactory motor speed is approximately 3600 R. P. M.

It is intended, of course, that the invention should not be limited to the specific embodiment or embodiments disclosed herein, since many modifications may be made, and it is contemplated, therefore, by the appended claims, to cover any such modifications as fall within the true spirit and scope of this invention.

Having thus described this invention, what is claimed and desired to be secured by Letters Patent is:

1. In a portable hammer having a reciprocable hammer element, a continuously rotating power driven means, energy storing means comprising a spring between said rotating means and said hammer, means movable on said hammer element and operable by said power means to compress said spring, said elements being constructed and related to cause hammer operating energy to be stored in said spring when said hammer element is at the limit of its working stroke, and means controlled by said rotating means simultaneously to raise said hammer element and said energy loaded spring and release said energy at the limit of the nonworking stroke of said hammer element to cause a working stroke.

2. A portable hammer comprising a continuously rotating power driven means, a reciprocable hammer element, energy storing means between said rotating means and said hammer element and normally tending to move said ham-

mer element to one limit of its stroke, means to cause energy to be stored in said storing means when said hammer element is at said one limit of its stroke, and means controlled by said rotating means to cause free movement of said hammer element to the limit of its nonworking stroke and then quickly release said stored energy to perform an unrestricted working stroke.

3. A hammer of the character described comprising a reciprocable hammer element, a power shaft, a compression spring on said hammer element and bodily movable therewith, means for compressing said spring with each revolution of said power shaft, normally ineffective pawl means operable by and during each rotation of said power shaft, and manually operable means to make said pawl means effective during each rotation of said power shaft to engage said hammer element and move said element and said compression spring to the limit of the nonworking stroke and quickly release said hammer element to enable said spring to cause a working stroke thereof.

4. In a portable power hammer of the character described, a continuously rotatable eccentric associated with a reciprocable hammer element, an eccentric strap on said eccentric and having a pivot slot angular to the axis thereof, a cross head on said hammer element and movable longitudinally of said hammer element and having a movable pivot in said pivot slot, a compression spring between said cross head and said hammer element, a pawl lug on said eccentric and normally movable therewith in a path out of the path of said hammer element, and manually operable means for moving said pivot in said slot to change the relationship of said eccentric strap to said eccentric so that said pawl lug intermittently moves in the path of said hammer element to move and release said hammer element and spring for a working stroke.

5. A power operated portable hammer comprising a casing having a laterally extending handle, a reciprocating hammer element in said casing, a power shaft extending through said handle in perpendicular axial alignment with the axis of said hammer element, an eccentric on said power shaft in alignment with said hammer element, a slideable cross head on said hammer element, a pivot for said eccentric strap on said cross head, a compression spring between said cross head and said hammer element, a pawl on said eccentric strap and normally out of operative engagement with said hammer element, a trigger adjacent said handle and operable to move said pivot to change the relationship of said pivoted eccentric strap to said eccentric whereby, during each revolution of said eccentric, said pawl will engage and move said hammer element to the limit of its nonworking stroke and release.

6. A portable power hammer comprising a casing, a hammer element mounted for limited reciprocation in said casing and having a working head extending therefrom only a restricted portion of its stroke so that the work is prevented by said casing from following said hammer head, a power driven, continuously rotatable eccentric, a compression spring between said eccentric and said hammer head and arranged to be compressed during alternate half cycles of said eccentric with said hammer element at rest, and pawl means on said eccentric and adapted to bodily move said hammer element and compressed spring to non-

working position entirely within said casing and quickly release said hammer element for a working stroke.

7. A portable power hammer comprising a casing, a hammer element mounted for limited reciprocation in said casing and having a working head extending therefrom only a restricted portion of its stroke so that the work is prevented by said casing from following said hammer head, a power driven, continuously rotatable eccentric, a compression spring between said eccentric and said hammer head and arranged to be compressed during alternate half cycles of said eccentric with said hammer element at rest, pawl means on said eccentric and adapted to bodily move said hammer element and compressed spring to non-working position entirely within said casing and quickly release said hammer element for a working stroke, said pawl being normally ineffective to cause operation of said hammer, and means controllable by an operator for making said pawl effective or ineffective at will.

8. A portable power hammer comprising a casing, a hammer element mounted for limited reciprocation in said casing and extending therefrom only a restricted portion of its stroke so that the work is prevented by said casing from following the hammer element, a pawl mounted on a floating pivot for lateral movement relative to said hammer element, said pivot being movable relative to said hammer element, a spring normally urging relative movement of said pivot and said hammer element, a trip lug on said hammer element for engagement by said pawl, and continuously operable means to alternately move said pivot to store energy in said spring with said hammer element at the limit of its working stroke and to cause said pawl to move said hammer element to the opposite limit of its stroke and quickly release said energy loaded spring and said hammer element for a working stroke.

9. A hammer of the character described comprising a comparatively small diameter elongated casing having a laterally extending handle, a reciprocating hammer element in said casing and having a bearing adjacent each end thereof, adjustable resilient means adjacent the upper end of said casing to cushion and limit the working stroke of said hammer element, a power shaft extending through said handle and through an opening in said hammer element, an eccentric on said shaft in alignment with said hammer element, an eccentric strap on said eccentric, a cross head on said hammer element between said eccentric strap and the working end of said hammer element, a compression spring between said cross head and the working end of said hammer element, said cross head having an element movable parallel with the axis of said eccentric strap and having an angular tooth thereon in mesh with complementary angular teeth on said eccentric strap to form a pivot for said strap, a pawl lug on said eccentric strap and normally ineffective to engage said hammer element, and trigger means associated with said handle to move said toothed cross-head element to position said eccentric so that said pawl lug will engage and move said hammer element to the limit of its nonworking stroke and release said element during each revolution of said eccentric.

10. A portable hammer comprising a casing having a laterally extending handle, a longitudinal reciprocating hammer element in said casing, an eccentric in said casing, a transmission ex-

tending through said handle for continuous operation of said eccentric and adapted for operative connection to a power source, an eccentric strap on said eccentric, a floating pivot for said eccentric strap to cause oscillation of said strap and vertical reciprocation of said pivot during each revolution of said eccentric, a spring between said pivot and said hammer element continuously urging relative movement thereof whereby energy is stored in said spring during partial rotation of said eccentric, and a pawl lug on said eccentric, said lug being adapted during further movement of said eccentric to engage and move said hammer element in one direction and during further movement to release said hammer element to enable said stored energy to cause a working stroke of said hammer.

11. A portable power hammer comprising a casing having a laterally extending handle, a hammer element mounted for limited reciprocation in said casing and having a hammer head, a power shaft extending through said handle and having an eccentric thereon in alignment with said hammer element, a cross head slideable on said hammer element between said eccentric and said hammer head, a compression spring between said cross head and said hammer head, an eccentric strap on said eccentric and provided with a pair of angularly positioned gear teeth, said cross head including a transversely movable element having an angular gear tooth meshing with the teeth on said eccentric strap and forming a pivot therefor whereby said spring is compressed with each revolution of said eccentric, a pawl lug on said eccentric and adapted to enter beneath a shoulder on said hammer element and raise and release said hammer element with each pivotal movement of said eccentric strap, said pivot tooth element normally being positioned to prevent hammer operation by said pawl lug, a manually operable trigger adjacent said handle, and means between said trigger and said pivot element to move said pivot element by operation of said trigger so that the angular relationship of said pivot teeth will position said eccentric to cause intermittent hammer engagement by said pawl lug.

12. An anvil supporting, substantially U-shaped yoke for a portable hammer unit comprising an anvil supporting arm, a hammer supporting arm, means connecting said arms for relative movement, adjustable means to enable adjustment of said arms to and from each other while retaining the same relative angular relationship, said connecting means comprising telescopic means for retaining said arms in alignment, said adjustable means comprising a manually operable cam for moving said arms toward each other and spring means tending to separate said arms.

13. A portable hammer of the character described comprising a casing having a laterally extending handle, a power shaft extending through said handle, a hammer element in said casing and operable by said power shaft, a substantially U-shaped yoke pivotally connected with said casing and having a portion in interlocking engagement with a complementary portion of said handle when said handle is in alignment with said yoke, said pivotal connection and said portions being constructed to enable removal of said yoke by rotary movement of said casing and handle on said pivotal connection to separate said portions and an anvil supported on the free

arm of said yoke in alignment with said hammer element.

14. A hammer of the character described comprising a vertical casing, a hammer element assembly longitudinally reciprocable in said casing and having a bearing at each end thereof, said hammer element being insertable longitudinally in said casing and having a compression spring thereon adapted when compressed and released to operate said hammer, retaining means adjacent one bearing and adapted to secure said hammer assembly in said casing for limited movement, spring means between said retaining means and said casing to limit the working stroke of said hammer assembly, a laterally extending hollow handle on said casing, a drive shaft assembly in said handle having an eccentric thereon positionable in the axial plane of said hammer element and having bushing bearings positionable in said casing, a bushing adapted to be threaded in said handle and adapted to retain said shaft assembly, and means on said eccentric for com-

pressing said hammer element spring and then moving said element and spring to the limit of the nonworking stroke and then releasing said element for a working stroke, said shaft assembly being insertable through said handle and said hammer element so that all parts are in completely operative relationship.

15. In a portable hammer of the character described, a hammer unit having a laterally extending handle, a substantially U-shaped anvil supporting yoke extending under said handle and having a vertical pivotal connection with said hammer unit adjacent the inner end of said handle, said pivotal connection having interlocking portions releasable by a partial rotation of said hammer unit, a releasable interlocking connection between said yoke and the outer end of said handle, and a hammer controlling trigger positioned under said handle, said yoke being formed between said interlocking connections to provide a trigger guard.

RAGNAR E. SKOGLUND.
